UNITED STATES PATENT OFFICE.

ROY M. MUSGROVE, OF SALT LAKE CITY, UTAH, AND FRED R. HOWARD, OF POCATELLO, IDAHO, ASSIGNEES TO MUSGROVE HOWARD AND CO. CORPORATION, OF SALT LAKE CITY, UTAH, A CORPORATION OF IDAHO.

MAIN-ROD CONNECTION.

1,120,519.

Specification of Letters Patent.

Patented Dec. 8, 1914.

Application filed July 22, 1914. Serial No. 852,363.

To all whom it may concern:

Be it known that we, ROY M. MUSGROVE, a resident of Salt Lake City, in the county of Salt Lake and State of Utah, and FRED R. HOWARD, a resident of Pocatello, in the county of Bannock and State of Idaho, citizens of the United States, have invented certain new and useful Improvements in Main-Rod Connections, of which the following is 10 a specification.

Our invention relates to connecting rods, particularly to those connecting the driving wheels of locomotives, and the main object thereof is to distribute the strain of the engine over all of the pins of such wheels 15 equally.

A further object is to provide a connecting rod for two driving wheels and with which rod the driving rod of the locomotive 20 is directly connected, instead of directly to the main pin as at present, thus relieving the main pin of a greater part of the strain now exerted thereon.

A further object is to provide supplemental rods for other driving wheels, if there 25 are more than two, and which supplemental rods are in direct connection with the main connecting rod, it being understood that the number of wheels mentioned applies to but 30 one side of a locomotive.

A further object is to provide such connecting rods which permit of the driving rod being connected with the driving wheel farthest removed from the cylinder, where- 35 by an increased leverage results; and a fur- ther object is to so construct the parts of our invention as not to interfere with the position or operation of the valve motion crank-arms or connections now employed, 40 such as the Walschaert; and further objects are to provide such devices which are readily installed on present type locomotives, which, by distributing the strain on all wheels equally, gain one-eighth more power, 45 materially reduce the wear on the tires, particularly on the main wheel, materially reduce the wear on the driving boxes, particu- 50 larly the main wheel boxes, and enables a locomotive to start more easily as all wheels are under equal starting strain; and which does not change the relative positions of any of the conventional parts of the locomotive.

Our invention is fully described in the fol-

lowing specification, of which the accom- 55 panying drawings form a part, in which the separate parts are designated by the same reference characters in each of the views, and in which:—

Figure 1 is a side elevation of a locomotive provided with our invention; Fig. 2 is a fragmentary, perspective, view of one end of our main connecting rod, detached, and greatly enlarged; and Fig. 3 is a similar view of the opposite end thereof, and showing a supplemental rod connected therewith.

In the drawings forming a part of this application we have shown a locomotive provided with three driving wheels 5, 6 and 7, 60 having crank-pins 5^a, 6^a, and 7^a, respectively, and on the first of which is shown the crank-arm 8 of the usual or any desired valve motion, and with which our invention does not interfere in the least.

It is the practice at present with locomotives having six drivers, three on a side, to connect the driving rod 9 directly with the crank-pin of the central driver, 6^a as shown in the drawings, and then connect this pin 80 with the other pins by means of a side rod, thus exerting the full power of the engine on the main pin 6^a and which, in turn, transmitted the power to the two other pins, and this system results in nearly twice more engine strain on the main pin than is borne by the other pins; further, in starting, this pin receives the first engine impulse and, accordingly, the main driver is revolved in a 85 degree before the other drivers, this result- 90 ing in what is known as quarter slipped tires; further, as the initial engine strain is applied directly to the main driver, the journal boxes thereof are under a materially greater strain than are those of the other 95 drivers, resulting in a proportionate wear and replacement of the bearings; further, by the present system of driving rod connection, a relatively shorter leverage thereof results than if said driving rod were connected 100 with the rear driver, as shown in the drawings with my invention. We, therefore, pro-

vide a main connecting rod 10 having a hole 11 therein to receive the crank-pin 5^a of the driver 5, at one end, and the opposite end 105 being bored for the crank-pin 6^a, said end being continued for a short distance where it is forked to form a knuckle-joint 12 with

a supplemental connecting rod 13 also bored, as shown at 14, for the reception of a pivot bolt 15 which also passes through the end of the main rod 10, said main rod being provided with a bore 16 for the pin 6^a and said supplemental rod 13 with a bore for the pin 7^a, at 17, Fig. 1.

The main rod 10 is provided, adjacent its rear end, but forward of the axle of the 10 wheel 5, in the position of the parts as shown, with a socket 18 to receive the outer end of the driving rod 9, a bore 19 being provided, Fig. 2, for the reception of a pivot pin 20 which also passes through the end of 15 the driving rod, and it will be seen that these elements of my invention are readily applicable to conventional locomotives.

The power from the engine cylinder is applied through the driving rod 9 directly to 20 the main connecting rod 10 and thus to all of the crank-pins of the three drivers at the same instant and in the same degree, thus distributing the strain equally over all said drivers and their bearings and, inasmuch as 25 no crank-pin 5^a, 6^a, or 7^a, carries more than one rod, and not two as at present, the strain on said pins does not come upon their outer ends but equally over the entire lengths thereof, and thus minimizing the possibility 30 of breaking said pins. Moreover, the driving rod 9 is of a considerably increased leverage over that possessed by the same when connected with the central driver, thus greatly increasing the hauling ability of the 35 locomotive and making it more efficient on grades, but the main feature of this driving rod connection is that none of the drivers carries a greater motive strain than another.

Our invention is very simple in construction, installation and operation, and comparatively inexpensive and, while we have shown a present preferred method of reducing our invention to practice, and certain specific details of construction, we do 40

not limit ourselves thereto, but may make 45 various changes therein and modifications thereover, within the scope of the following claims, without departing from the spirit of our invention, or sacrificing its advantages and, with such reservation,

What we claim as new, and desire to secure by Letters Patent, is:—

1. The combination with the driving wheels of a locomotive having, each, a crank-pin thereon, of a driving rod, a connecting rod in operative connection with the crank-pins of two of said wheels, and a connecting rod pivoted to said first named connecting rod and in operable connection with another of said crank-pins, said driving rod being in pivotal connection with said first named connecting rod.

2. The combination with the driving wheels of a locomotive having, each, a crank-pin thereon, of a driving rod, a connecting rod in operative connection with two of said pins, and provided with a socket adjacent one end to receive the outer end of said driving rod, pivotally, and with a forwardly directed member at its other end, and a supplemental connecting rod in pivotal connection with said forwardly directed member and in operable connection with another crank-pin.

In testimony whereof I have signed my name to this specification in the presence of the subscribing witnesses.

ROY M. MUSGROVE.
